Specification for Design.

Patented Nov. 19, 1918.

Application filed January 23, 1918. Serial No. 213,422. Term of patent 14 years.

To all whom it may concern:

Be it known that I, RONALD E. BOOTH, a subject of the King of England, residing at Seattle, in the county of King and State of Washington, have invented a new, original, and ornamental Design for a Velocipede, of which the following is a specification, reference being had to the accompanying drawing, forming part thereof.

Figure 1 is a side elevational view of a child's velocipede adapted to be propelled by the feet of the rider engaging the ground. Fig. 2 is a plan view, and Fig. 3 a front elevational view of the same.

I claim;—

The ornamental design for a velocipede, as shown.

RONALD E. BOOTH.
